COVERED BOXES OR CARTONS

Kenneth T. Butterly, Kalamazoo, Mich., assignor to
Sutherland Paper Company, Kalamazoo, Mich.

Application June 23, 1951, Serial No. 233,170

2 Claims. (Cl. 229—45)

This invention relates to improvements in covered 15 boxes or cartons.

The main objects of this invention are:

First, to provide a covered box or carton in which the cover is effectively retained for handling of the box and at the same time permits limited relative telescoping movement between the covering and the box body.

Second, to provide a covered box or carton in which the cover telescopes over the body, the cover and body having interlocking parts which may be quickly engaged or disengaged as occasion requires.

Third, to provide a covered box or carton having these advantages which may be economically produced from carton or container stock.

Objects relating to details and economies of the invention will appear from the description to follow. The invention is pointed out in the claims.

A preferred embodiment of the invention is illustrated in the accompanying drawings, in which:

Fig. 1 is a perspective view of a covered box or carton embodying my invention, one position of the cover being indicated by full lines and another position being indicated by dotted lines.

Fig. 2 is an end elevational view of the body member and cover member in separated position showing structural details thereof prior to the closing of the cover and the interlocking engagement thereof with the body member.

Fig. 3 is an end elevational view showing the cover in closed position prior to the interlocking engagement of the retaining tongues thereof with the body member.

Fig. 4 is a fragmentary perspective view illustrating the manner of engaging the retaining tongues of the cover member with openings provided therefor in the body member.

Fig. 5 is an enlarged fragmentary inside view in section on a line corresponding to line 5—5 of Fig. 1.

Fig. 6 is a plan view of the cover member blank in the flat or extended position.

Fig. 7 is a plan view of the body member blank in the flat or extended position.

Certain food products, such as fresh mushrooms, under certain conditions grow or expand substantially after being packaged for merchandizing. This may result in the bruising and damaging and discoloring of the product and in certain forms of packages that have been used, the breaking of the package. I have illustrated my invention in the accompanying drawing as embodied by me in boxes or cartons primarily designed for the packaging of fresh mushrooms.

The embodiment of my invention illustrated comprises a box body member designated generally by the numeral 1 and a cover member designated generally by the numeral 2 and telescopically engageable with the body member. The body member is formed from an integral blank designated generally by the numeral 3 (Fig. 7)

2

while the cover member is formed of an integral blank designated by the numeral 4 (Fig. 6).

The body member comprises a bottom 5, side walls 6—6 hingedly connected to the bottom at 7—7 and end walls 8—8 hingedly connected to the bottom at 9—9. The end walls are provided with corner flaps 10 hingedly connected thereto at 11 and provided with upwardly projecting tongues 12 on their outer side edges. The side walls are provided with angled slits 13 which are adapted 10 to receive the corner flaps, the portions 14 defined by the slits 13 being deflectable to facilitate the insertion of the corner flaps and the engagement of the tongues 12 with the upper edges of the upper angled portions of the corner flaps, thus supporting the supporting walls in erected position.

The cover member is of such size as to telescope loosely over the body member and it comprises the top wall 15, side walls 16 hingedly connected to the top wall at 17 and walls 18 hingedly connected to the top wall 15 at 19. The side walls 16 are provided with corner flaps 20 having upwardly projecting tongues 21 on their outer side edges while the end walls have angled slits 22 adapted to receive the portions of the corner flaps, the slits 22 defining deflectable portions 23 facilitating the 25 engagement of the corner flaps. It will be noted that in the body member the corner flaps are on the end walls while in the cover member they are on the side walls. The purpose of this is to bring the corner flaps of the 30 cover member and body member out of alignment so that there is less likelihood of their engaging. The terms side and end walls are used as a matter of convenience in describing the parts and not as a matter of dimension limitation.

The walls 8 of the body member are provided with 35 vertical U-shaped slits 24 defining openings 25 which are normally closed by the depending tongues 26. Corresponding walls or end walls 18 of the cover member are provided with vertical angled slits 27 defining dovetailed tongues 28 aligned with the openings 25 when 40 the cover is closed or telescoped over the body. To prevent the tongues being distorted or broken off in handling the blanks, the slits 27 preferably terminate adjacent to but in spaced relation to the bottom edges 29 of the cover walls 18, the unslit portions 30 (see Fig. 6) 45 being readily broken or fractured when the cover is telescoped over the body and pressure applied to the tongues to push them through the openings 25 and into interlocking engagement therewith. With the tongues 28 in locked or engaged position, the cover is retained upon 50 the box for handling but may expand or move outwardly as is indicated by the dotted lines 32 in Fig. 1.

When it is desired to remove the cover, fingers may be inserted through the openings 25 to engage the bottom edges of the tongues and pull them outwardly 55 through the openings and if it is desired to reclose the box, it is only necessary to close the cover and push inwardly on the tongues.

The structure of the box and cover member insofar 60 as the interlocking of the walls thereof are concerned is substantially that of my Letters Patent No. 2,712,409, issued July 5, 1955. I have illustrated that type of structure as it illustrates the form in which I have embodied my present invention commercially.

65 The openings 33 in the cover and body member are for ventilation.

I have illustrated and described my invention in a highly practical commercial embodiment thereof. I have not attempted to illustrate or describe other embodiments which I contemplate as it is believed the disclosure 70 will enable those skilled in the art to embody or adapt my invention as may be desired.

Having thus described my invention, what I claim as new and desire to secure by Letters Patent is:

1. A covered box comprising a body member having four upstanding walls, one opposed pair of walls having centrally positioned vertical U-shaped slits therein spaced from the upper edges of the walls and defining vertical openings and closures for the openings hingedly connected to the upper edges thereof and bodily swingable through the openings, and a four-walled cover member telescopingly embracing the walls of the body member, the opposed pair of cover member walls corresponding to the walls of the body member having the openings therein having laterally spaced angled slits extending vertically from the lower edges thereof and defining swingable tongues having heads at their lower ends of a width exceeding the width of the openings in said body member walls and aligned therewith when the cover is closed and adapted to be inserted therethrough by inward thrust on the tongues to engage the heads of the tongues with the inner sides of the body member walls, the upper edges of the heads being spaced substantially from the upper ends of said body member openings when the cover is in fully closed position and the tongues inserted in said openings in said body member thereby permitting substantial vertical movement of the cover relative to the body member to vary the capacity of the box while retaining the cover on the body member, said openings in said body member providing finger openings, permitting the engagement of the lower edges of the engaged tongues for disengaging the tongues from the body member.

2. A covered box comprising a body member having four upstanding walls, one opposed pair of walls having centrally positioned vertically elongated openings therein, and a four-walled cover member telescopingly embracing the walls of the body member, the opposed pair of cover

member walls corresponding to the walls of the body member having the openings therein having laterally spaced slits extending vertically from the lower edges thereof and defining swingable tongues having heads at their lower ends of a width exceeding the width of the openings in said body member walls and aligned therewith when the cover is closed and insertable therethrough by inward thrust on the tongues to engage the heads of the tongues with the inner sides of the body member walls, the upper edges of the heads being spaced substantially from the upper ends of said body member openings when the cover is in fully closed position and the tongues inserted in said openings in said body member thereby permitting substantial vertical movement of the cover relative to the body member to vary the capacity of the box while retaining the cover on the body member, said openings in said body member providing finger openings permitting the engagement of the lower edges of the engaged tongues for disengaging the tongues from the body member.
